CLAIM

The ornamental design for an air filter, as shown and described.

DESCRIPTION

FIG. 1 is a front, right, and top perspective view of an air filter, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another front, right, and top perspective view of the air filter of FIG. 1 in one state.

The broken lines depict portions of the air filter in which the design is embodied that form no part of the claimed design.

1 Claim, 9 Drawing Sheets
